FIG. 3 is a left side elevational view thereof;

FIG. 4 is a front side elevational view thereof;

FIG. 5 is an enlarged front isometric view of the clothing
belt taken from lines 5-5 in FIG. 1;

FIG. 6 is an enlarged front isometric view of the clothing
belt taken from lines 6-6 in FIG. 1;

FIG. 7 is an enlarged rear isometric view of the clothing belt
taken from lines 7-7 in FIG. 2;

FIG. 8 is an enlarged rear isometric view of the clothing belt
taken from lines 8-8 in FIG. 2;

FIG. 9 is an enlarged left side elevational view of the
clothing belt taken from lines 9-9 in FIG. 3; and,

FIG. 10 is an enlarged left side elevational view of the
clothing belt taken from lines 10-10 in FIG. 3.

The broken lines shown in the drawings illustrate the bounds
of the enlargements, and form no part of the claimed design.
